United States Patent Office

Des. 183,109
Patented June 24, 1958

183,109

INCINERATOR

Nickolas Soltesz, Toledo, Ohio

Application December 19, 1957, Serial No. 48,965

Term of patent 14 years

(Cl. D81—1)

FIG. 1.

FIG. 3.

FIG. 2.

Fig. 1 is a front elevation of an incinerator embodying my new design, with the cover raised;

Fig. 2 is a side view thereof, and

Fig. 3 is a top view.

I claim:

The ornamental design for an incinerator, substantially as shown.
